PORTABLE AND EXTENSIBLE PROPAGATING DEVICE

Filed July 3, 1926

UNITED STATES PATENT OFFICE

GERTRUDE EVELEEN EDWARDS, OF SABLE RIVER, WEST, NOVA SCOTIA, CANADA

PORTABLE AND EXTENSIBLE PROPAGATING DEVICE

Application filed July 3, 1926. Serial No. 120,460.

The object of this invention is to provide a device of the character indicated, intended for use in truck gardens, and in private gardens, for the purpose of protecting or forcing the growth of young plants.

A further object is to provide a device which is of such reasonable cost that it may be employed by many individuals unable to go to the expense of building a greenhouse, the device here referred to being of simple construction, adapted to be quickly set up, and as quickly transferred to a new position, and being constructed in units so that it may be indefinitely extended, the end joints being closed if desired by glass or other end sections, and each of the units being provided with a cut away portion forming an end extension adapted to overlap an oppositely located extension of the adjacent unit.

A further object is to provide units which may be constructed throughout of wood, or may be constructed with glass panels.

A further object is to provide for connecting a plurality of side members, for forming one unit, by means of hinges, and in such manner that when not in use, these members will lie flat and may be stored in large numbers, within a very small space.

A further object is to provide for securing the units, so that they will not be displaced by wind pressure.

With the foregoing and other objects in view, the invention consists in the novel construction and arrangement of elements described, illustrated and claimed, it being understood that modifications may be made within the scope of the claim without departing from the spirit of the invention.

In the drawing forming part of this application,

Figure 1 is a view of the device in side elevation two units being shown.

Figure 2 is a view in end elevation.

Figure 3 is a section on line 3—3 of Figure 1, showing the overlapping ends of the units.

Figure 4 is a section on line 4—4 of Figure 1, showing the relative position of the elements at the hinge joint.

Figure 5 is a perspective view of a rod or

stake, of particular form, employed for securing the units to the ground.

The units each consist of two sash members or frames, designated 10 and 12, or may consist of two side members, either formed of framed elements, or formed of a single board or sheet of other suitable material.

In Figure 1 the sash members each comprise an upper and lower longitudinal strip, the lower strip being designated 10', and the end strips being shown at 11 and 13. The glass panes or panels are designated 14, and any suitable number may be employed, but a convenient standard frame or sash includes four glass panels.

The end members of the sashes or frames are cut away as illustrated more particularly in Figure 3, and opposite ends of each sash are chamfered to form an extension 16 on one end, and at the outer side of the frame,—the other end of each sash member being cut away to form an inner extension 17. These extensions or projections 16 and 17 of adjacent units overlap as shown in Figure 3 and permit of indefinite extension of the structure as a whole. It will be observed that abutting longitudinal and connecting elements of adjacent units form joint connections with flush exterior surfaces to provide continuous reinforced side and upper edge portions for a series of units.

Each upper strip is beveled as shown at 19, and hinges 20 are mortised into the strips, the rolled portions of the hinges projecting beyond the angle formed by the oppositely located strips, so that the side members may be folded flat, when not in use, and when moved to the position shown in Figures 2 and 4, the sash members will be approximately perpendicular with reference to each other, but the angle may vary.

Triangular end frames 25 each carry downwardly extending pins 26, adapted to be forced into the ground, and these end members are adapted to be held in vertical position by braces such as 27.

The retaining devices for the side members 10 and 12 of each unit are shown in Figures 1, 2 and 5, and from an inspection of these views it will be apparent that stakes 28 are em-

ployed, each being provided with a head or cross member 29, the shank portion, or stake proper, being inserted thru an eye member 30 secured to the lower strip 10' of each side member. The stakes are forced into the ground, in most instances, by hand, and may be easily removed when desired. The device, although of light and readily portable construction, is firmly secured in place, and serves the purpose intended, under all circumstances in which a similar substitute for a permanently erected greenhouse may be employed.

Having described the invention what is claimed is:—

15 In a device of the class described, a plurality of units each comprising a pair of side members hinged at corresponding edges, their free edges being adapted to be positioned in spaced relation, and the ends of each side member being formed with a longitudinally extending projection, the projection at one end of each member being on the outer side of that member, and the projection on the other end being on the inner side, the side members constituting frames including longitudinal elements and elements extending between and connecting the longitudinal elements, abutting longitudinal and connecting elements of adjacent units forming joint connections with flush exterior surfaces, to provide continuous reenforced side and upper edge portions for a series of units thus assembled.

35 In testimony whereof I affix my signature.
GERTRUDE EVELEEN EDWARDS.
